UNITED STATES PATENT OFFICE.

CHARLES V. LINDHOLM, OF CHICAGO, ILLINOIS.

FIRE-ESCAPE.

1,002,999.

Specification of Letters Patent. Patented Sept. 12, 1911.

Application filed April 21, 1911. Serial No. 622,572.

To all whom it may concern:

Be it known that I, CHARLES V. LINDHOLM, a citizen of the United States, and a resident of the city of Chicago, county of 5 Cook, and State of Illinois, have invented certain new and useful Improvements in Fire-Escapes, of which the following is a specification.

My invention relates to improvements in 10 fire escapes and more specifically to the lower pivoted stair-section of a conventional fire escape. At the present time this stair-section of the fire escape is provided at its pivoted end with a counter weight which is 15 secured to the outer stringer thereof. It has been found that unless provision is made, the corner at the free end of the stair-section opposite to that at which the counter weight is secured sags.

20 The object of the present invention is to so construct this stair-section of the fire escape that the corner thereof opposite that to which the counter weight is secured will be prevented from sagging.

25 A further object is the provision of a fire escape construction as mentioned, which will be durable and economical and efficient in operation.

Other objects will appear hereinafter.

30 With these objects in view my invention consists in a fire escape characterized as above mentioned and in certain details of construction and arrangement of parts all as will be hereinafter more fully described 35 and particularly pointed out in the appended claims.

My invention will be more readily understood by reference to the accompanying drawing forming a part of this specification, and in which,

40 Figure 1 is an inner side elevation of a swinging fire escape stair-section embodying my invention, the same being shown in incomplete condition, Fig. 2 is a similar 45 view thereof completed, Fig. 3 is a slightly enlarged detail section taken on line $x-x$ of Fig. 2, Fig. 4 is a detail perspective view of one of the step tread-bars, and Fig. 5 is a detail of one of the end members included 50 in each of the steps.

The preferred form of my construction as

illustrated in the drawing comprises outer and inner stringers, the former being formed of two separated parallel longitudinal bars 1 and 2 and the latter of correspondingly positioned bars 3 and 4. Extending between and connecting said stringers at intervals are the steps which are arranged in the usual manner so that when the free end of the stair-section is lowered 55 into contact with the ground, said steps will assume a horizontal position. Each of the steps comprises end pieces 5 which are rigidly secured to the stringer bars at 6. Extending between the end pieces 5 are 60 tread-forming bars 7, the respective ends of said bars 7 being flattened for snug engagement with correspondingly formed slots 9 provided in said end pieces, a rigid step construction being thus provided. 70

The stair-section is shown mounted upon the usual pivot rod 10, the structure or building to which the inner end of said pivot bar is secured, not being shown. Arranged beyond the pivot rod 10 is the 75 counter weight 11 which is connected with the stair-section by means of the channel bar 12, the latter being rigidly secured to the pivoted end of the outer stringer. Also arranged upon the outer stringer is the 80 usual guard rail 13.

The lower ends of the stringer bars 3 and 4 are connected by means of a plate 14, the latter being secured to said bars by means of bolts 15 and nuts 16 threaded upon said 85 bolts. The opposite ends of the stringer bars 3 and 4 are connected by means of a plate 17, the respective edges of said plate being secured to said bars 4 and 5 by means of bolts 18 and 18' and nuts 19 and 19' 90 threaded respectively upon said bolts.

In constructing the stair-section the same is completed to every detail as above set forth with the exception of the insertion of the bolts 18' and the nuts 19' which are 95 omitted. The structure in this condition is shown in Fig. 1 where it will be noted that the lower end of the inner stringer or the corner of the stair-section opposite to that bearing the counter weight sags. Before 100 said bolts 18' and nuts 19' are applied, the stringer bar 3 through the medium of the

lever 20 is forced bodily toward said plate 17, this being done by engaging the lower bifurcated end of said lever with a stud 21 projecting from the bar 4 and forcing the 5 intermediate portion of said lever against the stud 22 projecting from the bar 3 by engaging the upper or free end of said lever. By thus forcing the stringer bar 3 it will be observed that the lower end of the stringer 10 bar 4 will be forced upwardly, the entire structure being in fact strained in such a manner as to elevate the sagging corner of the stair-section bringing the same into the same horizontal plane with the correspond- 15 ing corner thereof as shown in Fig. 2. When said stringer bar 3 is so moved, the bolt holes therein will be brought into alinement with the bolt holes provided in the plate 17 whereupon the bolts 18' will be inserted into position and the nuts 19' threaded thereon in order to maintain the structure in the above-mentioned strained condition and hence the normally sagging corner thereof in proper position. Instead of the bolt holes being 20 drilled in the bar 3 before straining the same as above described, it is evident that if desired, the same may be drilled after said bar has been moved to proper position and after drilling the bolts 18' inserted therein.

25 30 With the construction as set forth the sagging in the pivoted stair-section of a fire escape which has been referred to may be avoided and with the expenditure of a minimum of time, labor and expense. A structure 35 of the construction as set forth is durable and economical and the same is adapted to efficiently serve in the capacity for which the same is designed.

While I have illustrated and described the 40 preferred form for carrying my invention into effect, this is capable of variation and modification without departing from the spirit of the invention. I therefore do not wish to be limited to the precise details of 45 construction as set forth, but desire to avail myself of such variations and modifications as come within the scope of the appended claims.

Having described my invention what I 50 claim as new and desire to secure by Letters Patent is:

1. A fire escape comprising a pivoted stair-section, said section comprising stringers and steps extending between and connecting said 55 stringers; a counter weight at one end of one of said stringers; and means for maintaining a condition of strain resulting from a force applied to the upper edge of the other of said stringers longitudinally thereof and reacting against the lower edge thereof in the opposite direction, substantially as described.

2. A fire escape comprising a pivoted stair-section, said section comprising stringers and

steps extending between and connecting said 65 stringers; a counter weight at one end of one of said stringers, the other of said stringers comprising two substantially parallel longitudinal bars; and means for maintaining a condition of strain resulting from a force 70 applied to the upper bar of said last-mentioned stringer longitudinally thereof and reacting against the lower bar of said stringer in the opposite direction, substantially as described.

3. A fire escape comprising a pivoted stair-section, said section comprising stringers and steps extending between and connecting said 80 stringers; a counter weight at one end of one of said stringers, the other of said stringers comprising two substantially parallel longitudinal bars; and plates connecting said 85 bars for maintaining a condition of strain resulting from a force applied to the upper bar of said last-mentioned stringer longitudinally thereof and reacting against the lower bar of said stringer in the opposite direction, substantially as described.

4. A fire escape comprising a pivoted stair-section, said section comprising stringers and 90 steps extending between and connecting said stringers; a counter weight at one end of one of said stringers, the other of said stringers comprising two substantially parallel longitudinal bars; and plates connecting said 95 bars at the respective extremities thereof for maintaining a condition of strain resulting from a force applied to the upper bar of said last-mentioned stringer longitudinally thereof and reacting against the lower bar 100 of said stringer in the opposite direction, substantially as described.

5. A fire escape comprising a pivoted stair-section, said stair-section comprising stringers and steps extending between and rigidly connecting said stringers, each of said 105 steps comprising end pieces and tread-forming bars extending between and rigidly secured in said end pieces, the other of said stringers comprising two substantially parallel longitudinal bars; and plates connecting said bars for maintaining a condition of strain resulting from a force applied to the upper bar of said last-mentioned stringer longitudinally thereof and reacting against 110 the lower bar of said stringer in the opposite direction, substantially as described.

6. The method of constructing the pivoted stair-section of a fire escape which consists in providing two stringers; in providing a 120 counter weight at one end of one of said stringers; in providing steps extending between and connecting said stringers; in forming the other of said stringers of two parallel separated longitudinal bars; in 125 rigidly connecting corresponding ends of the latter; in securing a connecting plate to the opposite end of one of said bars; in forcing

the free end of the other of said bars toward said plate so as to strain said bars; and in rigidly securing said free end of said free bar with said last-mentioned plate to maintain said bars in strained condition, substantially as described.

5 In testimony whereof I have signed my

name to this specification in the presence of two subscribing witnesses.

CHARLES V. LINDHOLM.
